DESIGN FOR A DRESS ENSEMBLE

Judith Woursell, New York, N. Y.

Application September 12, 1940, Serial No. 94,984

Term of patent 3½ years

To the Commissioner of Patents:

Be it known that I, Judith Woursell, a citizen of the United States, residing at 14 Sutton Place South, New York city, in the county of New York and State of New York, have invented a new, original, and ornamental Design for a Dress Ensemble, of which the following is a specification, reference being had to the accompanying drawing, forming part thereof.

Figure 1 is a front view of a dress ensemble showing my new design;

Figure 2 is a front view of the dress member;

Figure 3 is a rear view of the dress member; and

Figure 4 is a rear view of the jacket member.

The jacket and dress are of contrasting colors.

The girdle simulation at the waist line of the dress is formed of Shirred material and constitutes an integral part thereof.

I claim:

The ornamental design for a dress ensemble, substantially as shown and described.

JUDITH WOURSELL.
